UNITED STATES PATENT OFFICE

151,972

DESIGN FOR A FISH TYPE HARMONICA

Samuel Freimauer and Jack Skoloff,
Hillside, N. J.

Application August 16, 1947, Serial No. 140,924

Term of patent 14 years

(Cl. D56—1)

To all whom it may concern:

Be it known that we, Samuel Freimauer and Jack Skoloff, citizens of the United States, both residing at Hillside, in the county of Union, State of New Jersey, have invented a new, original, and ornamental Design for a Fish Type Harmonica, of which the following is a specification, reference being had to the accompanying drawing forming a part thereof.

In the drawing:

Figure 1 is a side elevational view of a fish type harmonica, showing our new design.

Figure 2 is a top view of Figure 1.

Figure 3 is a bottom view of Figure 1.

We claim:

The ornamental design for a fish type harmonica, as shown.

SAMUEL FREIMAUER.
JACK SKOLOFF.
